UNITED STATES PATENT OFFICE.

ANTON CIMFL, OF RICE LAKE, WISCONSIN.

ATTACHMENT FOR GRADERS.

Application filed June 22, 1921. Serial No. 479,491.

To all whom it may concern:

Be it known that I, ANTON CIMFL, a citizen of the United States, and a resident of Rice Lake, in the county of Barron and State of Wisconsin, have invented a new and Improved Attachment for Graders, of which the following is a full, clear, and exact description.

This invention relates to an attachment 10 for road grading or scraping machines and refers more particularly to a supporting shoe adapted for connection therewith for the purpose of bridging wash-outs or depressions in the side of the road to prevent 15 the rear outer supporting wheel and the blade from dropping down and cutting the wash-out or depression deeper.

The invention further contemplates the provision of an attachment of this character 20 which is provided with means of adjustment whereby the same may be normally disposed out of contact with the road surface, said means being located within convenient reach of and operable by the operator 25 of the machine for lowering the same into contact with the road when desirable.

A still further object in view resides in the provision of a supporting shoe attachment which is simple and inexpensive to 30 manufacture, highly efficient in its purpose, and which is readily applicable to standard machines of this type without materially altering the same.

With the above recited and other objects 35 in view the invention resides in the novel construction, combination and arrangement of parts set forth in the following specification, particularly pointed out in the appended claims, and illustrated in the accompanying drawings, in which—

Figure 1 is a side view of a road grader equipped with a supporting shoe attachment constructed in accordance with the invention and illustrating the same out of contact with the road surface.

Fig. 2 is an enlarged rear elevation therof.

Referring to the drawings by characters of reference, 10 designates a road grader of any approved construction, the same being provided with front and rear supporting wheels 11 and 12 and the scraper blade

13. The attachment consists of a metal beam 14 bent at an angle to provide a road bed engaging shoe or runner 15 and a connecting arm 16, the latter being pivoted at 55 its free extremity as at 17 to the arch frame

18 of the machine. In order to provide means for raising or lowering the shoe or runner 15 into or out of contact with the surface of the road, a threaded shaft 19 is 60 provided, the same being pivotally connected as at 20 at its lower end to the shoe. The upper extremity thereof is designed to project through an opening 21 in the rear axle 22 of the vehicle. A suitable adjusting 65 sleeve 23 having an interiorly threaded bore receives the upper end of the shaft 19 and engages the bearing 24 on the axle 22 for effecting the raising and lowering of the shoe. A manipulating wheel 25 is secured 70 to the upper end of the sleeve for rotating the same. Preferably a lateral brace rod 26 is secured to the under side of the axle 27 and to the shaft adjacent its connection with the shoe. 75

In use and operation of the attachment the manipulating wheel 25 is normally actuated to lift the shoe and retain the same out of contact with the road surface. When the operator of the machine observes a rut, depression or wash-out in the side of the road, the hand wheel 25 is manipulated to lower the shoe into contact with the surface of the road whereby the same will bridge the depression and prevent the dropping or sinking of the rear outer supporting wheel into said depression. The loose earth being pushed in advance of the blade will fill in the ditch or depression, while the shoe 85 will serve to retain the blade on the same level. 90

It will thus be seen that a simple and inexpensive attachment for a grading machine is provided which will efficiently operate to prevent the dropping of the blade below the 95 level of the road should a depression or wash-out be encountered.

While there has been illustrated and described a single and preferred embodiment of the invention, no limitation is necessarily made to the precise structural details, as it is to be understood that variations and modifications which properly fall within the scope of the appended claims may be resorted to when found expedient. 100

Having thus described my invention, what I claim is:

1. The combination with a road grading machine, of an attachment therefor adapted to be thrown into a road surface engaging 110 position alongside of the rear supporting wheels for the purpose of bridging a de-

pression in the road bed to prevent the dropping of the rear wheels and the grader blade below the level of the road surface, said attachment comprising a runner having pivotal connection to the machine frame at its forward end to permit of vertical swinging movements thereof, an upstanding threaded stem having pivotal connection to said runner, and a rotary interiorly threaded manipulating member swivelly mounted on the grader above said runner and threadedly engaging the stem for effecting vertical adjustments of the runner.

2. An attachment for road grading machines comprising a longitudinally disposed runner having pivotal connection at its forward end to the machine in advance of one of the rear supporting wheels, and adjustable means of connection between the rear supporting axle and said runner for rigidly supporting the rear axle of the vehicle from the runner when the runner is adjusted to lie in a plane with the lower periphery of the rear supporting wheels, whereby said runner will bridge a depression in the road bed to prevent the dropping of the rear supporting wheels and the grader blade below the surface of the road, said means of connection comprising a vertically disposed stem having pivotal connection with the runner at its lower end, a manipulating nut engaged on said stem, and a swiveled connection between said nut and the grader for holding the nut against vertical movement to effect relative vertical movement of the stem upon rotation of the nut.

3. The combination with a road grading machine, of an attachment therefor comprising a longitudinally disposed runner having pivotal connection at its forward end to the machine in advance of the rear supporting wheels and extending longitudinally thereof beyond the rear of the rear supporting wheels, and means of connection between said runner and the rear of the machine for adjustably supporting the runner for vertical swinging movements,

whereby said runner may be lowered to a plane with the lower periphery of the wheel 50 for the purpose of bridging a depression adjacent the edge of the road to prevent the dropping of the rear wheels and the grading blade below the level of the road surface, said means of connection comprising 55 a vertically disposed threaded shaft pivotally connected at its lower end to the runner, an apertured portion in the axle of the grader, a nut having a centrally threaded bore swiveled on said axle with the bore in 60 alignment with the aperture, said threaded shaft extending through the aperture and threadedly engaged with the bore of the nut, and a transverse brace consisting of 65 telescopically connected sections having connection at their free ends respectively with the axle of the grader and with the threaded stem adjacent its pivotal connection with the runner.

4. The combination with a road grading machine, of an attachment therefor comprising a longitudinally disposed runner having pivotal connection at its forward end to the machine in advance of the rear supporting wheels and extending longitudinally thereof beyond the rear of the rear supporting wheels, means of connection between said runner and the rear of the machine comprising a vertical stem pivotally connected at its lower end to the runner and extending through a rotary manipulating member mounted on the grader for adjustably supporting the runner for vertical swinging movements, whereby said runner may be lowered to a plane with the 70 lower periphery of the wheel for the purpose of bridging a depression adjacent the edge of the road to prevent the dropping of the rear wheels and the grading blade below the level of the road surface, and a 75 telescopically adjustable brace element connected to the rear of the machine at one extremity and extending transversely thereof and having connection at its opposite extremity with the runner.

ANTON CIMFL.
